UNITED STATES PATENT OFFICE.

CLARENCE D. PLATT, OF BRIDGEPORT, CONNECTICUT.

SAFETY SWITCH.

Application filed December 18, 1922. Serial No. 607,524.

To all whom it may concern:

Be it known that I, CLARENCE D. PLATT, a citizen of the United States of America, and residing at Bridgeport, in the county of 5 Fairfield and State of Connecticut, have invented new and useful Improvements in Safety Switches, of which the following is a specification.

This invention relates to safety switches 10 of the type having a switch and fuses to protect the load circuit enclosed within a casing and a cover having a sliding panel to give access to the fuses when the cover is closed.

15 An object of the invention is to provide in a switch of this type a simple, rugged construction which prevents opening of the panel when the switch contacts are closed and closing of the contacts when the panel 20 is open.

A further object is to provide such a switch having a minimum number of parts, with consequent ease of assembly and cheapness of manufacture.

25 Fig. 1 is an end view partly in section showing the contacts open, the casing being sectioned along the line 1—1 of Fig. 4.

Fig. 2 is a front elevation of the switch casing with the cover closed, the switch 30 mechanism being indicated in dotted lines with the contacts closed.

Fig. 3 is a longitudinal section taken on the line 3—3 of Fig. 2 showing the contacts and panel closed.

35 Fig. 4 is a view similar to Fig. 3 but showing the contacts and panel open, part of the base being in elevation.

Fig. 5 is a perspective view of the movable contacts and the plate which connects 40 them to the operating bar, and

Fig. 6 is a perspective view of a hasp to lock the casing.

The invention is illustrated in connection with a double pole switch, having a box or 45 casing 7 and a cover 8 preferably hinged to one of the side walls of the casing. Secured to the back wall of the casing is an insulating base 9 having two fuse sockets 10 at its lower end, and a projection 11 extending 50 nearly to the cover. Posts 12 fixed to the base pivotally support the movable contacts or blades 13 which cooperate with the fixed spring contacts 14. The incoming line conductors may be connected to the 55 fixed contacts as by binding screws 15, while binding screws 34 connected to the fuse

sockets are provided to accommodate the load conductors.

The blades 13 are connected by an insulating cross bar 16, about midway of which 60 is secured an arcuate plate 17 as by the tangs 18 which may be headed over as shown. A crank shaped operating bar 19 pivoted in the side walls of the casing engages the edges of a notch 20 in the lower 65 edge of plate 17, which thus serves to interconnect the blades and operator.

To give access to the fuses the cover is apertured near its lower end, and a panel 21 is provided normally to close this aperture, guide rails 22 being secured to the opposite side walls of the cover to support the panel close to the inner surface of the cover and slidably relative thereto. A button 23 secured near the front edge of the 75 cover facilitates its operation and limits its movement by abutting against the edges of the aperture.

In order that the panel may be opened 80 only when the contacts are open, I provide on plate 17 an arm 24 extending when the contacts are closed into the path of movement of the panel and close to the rear edge thereof (Fig. 3). The end of arm 24 thus acts as a stop to prevent appreciable opening movement of the panel when the contacts are closed. When the contacts are open (Fig. 4) arm 24 is withdrawn from the path of movement of the panel into a slot 25 in the projection 11, so as to permit 90 free movement of the panel.

To prevent closing of the contacts when the panel is open, I carry the outer curved edge 26 of arm 24 beyond the plane of the panel and the flat portion of the cover, and 95 arch the cover at 27 to afford clearance for the plate when the panel is shut (Fig. 3). When the contacts and the panel are open, the panel stands in the path of the plate and thus prevents closing movement of the contacts. An attempt to close the contacts when the panel is open would tend to force the cover outwardly and might result in forcing it open sufficiently to permit such closing movement. I therefore bend over one edge 100 of plate 17 to form a marginal flange 28 which lies parallel and close to the lower surface of panel 21 when the contacts are open, and interlocks with a hook member such as the bar 29 secured longitudinally on the inner surface of the panel when the contacts are open (Figs. 1 and 4). Obviously 105 110

this construction permits free movement of the panel so long as the contacts are wide open, but until the panel is tight shut any closing movement of the contacts will merely bring the leading edge of the flange 28 into engagement with the hook member 29, and by inward pressure on the latter will counteract any tendency to force the cover open as above described.

10 When the switch and the sliding panel are both in the open position as shown in Fig. 4, the flange 28 on member 17 overstands or interlocks with the hook member 29 on the panel and thus prevents the opening of the 15 box cover while the parts are in this position.

I also provide a simple yet effective locking device consisting of a hasp 30 and an angular lug 31 secured to the end wall of the 20 casing and the side flange of the cover respectively. The hasp consists of a strip of sheet metal punched at one end to accommodate a rivet 32 by which it is pivoted to the casing, and slotted as at 33 to fit over lug 31 25 which may be punched to receive a padlock.

While I have described my invention in connection with a switch having two sets of contacts of the positive make and break type, obviously it is equally applicable to 30 switches with a different number of contacts and of other types. Moreover parts may be substituted for other parts, changed in shape, added or dispensed with entirely, all without departing from the spirit of my invention.

I claim:

1. In a safety switch, a casing, a cover having a panel slidable to open or close an aperture therein, a fixed contact, a movable 40 contact, an operating bar, and a member to interconnect the movable contact and bar and to prevent opening of the panel when the contacts are closed.

2. In a safety switch, a casing, a cover having a panel slidable to open or close an aperture therein, a fixed contact, a movable contact, an operating bar, and a member to interconnect the movable contact and bar and prevent closing of the contacts when the 50 panel is open.

3. In a safety switch, a casing, a cover therefor and having an aperture therein, a sliding panel to close said aperture, fixed switch contacts, movable switch contacts, a 55 cross-bar connecting said movable contacts, a switch operating crank, an arcuate plate secured to said cross-bar and having operable connection with said crank, a flange on said panel and a flange on said arcuate plate member to engage the flange on said panel, and prevent closing of the switch when the panel is in open position.

4. In a safety switch, a casing, a cover therefor having an opening, a slide for closing said opening, fuse sockets in one end

of the casing in line with said opening, stationary and movable contacts in the other end of the casing, an operating bar, a plate carried by said movable contact and connected to said operating bar, said plate having a portion obstructing the movement of said slide when the switch is closed and another portion obstructing the movement of the movable switch contact when the slide is open.

5. In a safety switch, a casing, a cover having a sliding panel to open or close an aperture therein, a pair of fixed contacts, a pair of movable contacts, an insulating cross bar connecting said movable contacts, a contact operator, and a plate secured to the cross bar and in engagement with the operator, said plate having an arm extending when the contacts are closed into the path of movement of the panel and near the rear edge thereof to prevent opening of the panel.

6. In a safety switch, a casing, a cover having a sliding panel to open or close an aperture therein, a pair of fixed contacts, a 90 pair of movable contacts, an insulating cross bar connecting said movable contacts, a contact operator, and a plate secured to the cross bar and in engagement with the operator, said panel when open serving as an 95 abutment for one edge of said plate to prevent closing of the contacts.

7. In a safety switch, a casing, a cover having a sliding panel to open or close an aperture therein, a pair of fixed contacts, a 100 pair of movable contacts, an insulating cross bar connecting said movable contacts, a plate secured to said cross bar, a contact operator, a hook member secured to the inner face of the panel and a marginal flange 105 on said plate adapted to interlock with said hook member when the panel is open to prevent closing of the contacts.

8. In a safety switch, a casing, a hinged cover therefor having an opening, a slide 110 for closing said opening, fuse sockets in said casing in line with said opening, stationary and movable switch contacts in said casing, a plate connected to said movable switch contact having a portion preventing the 115 opening movement of said slide when the switch is closed and having another portion preventing the closing of the switch when the slide is open and having another portion preventing the opening of the 120 hinged cover when the slide is open and the switch is open.

9. In a safety switch, a casing, a fixed contact, a movable contact, an operating bar mounted for rotation on an 125 axis transverse to the casing, a plate to interconnect the movable contact and operating bar, a cover for the casing having a flat body portion and an outwardly arched transverse portion, a panel 130

- slidable in the cover, and an arm on the plate extending beyond the plane of the flat portion of the cover into the path of movement of the panel and near the rear edge 5 thereof when the contacts are closed to prevent opening of the panel, said plate lying entirely below said panel when the contacts are open to permit opening of the panel, and said panel when open lying in the path of 10 movement of said plate to prevent closing movement of the contacts.
10. In a safety switch, a casing having walls, an insulating base secured to the rear wall of the casing and having an outwardly 15 extending transverse projection, said base having provision for fuse sockets at one side of the projection, a number of fixed contacts secured to the base on the other side of the projection, a number of pivotally mounted blades to cooperate with said contacts, a cas- 20 ing cover having a sliding panel, a plate movable with the blades and having an arm extending into the path of movement of the panel when the contacts are closed, said pro- jection having a slot to accommodate said 25 plate arm, and means for moving the blades to open position and moving the plate arm into the slot and out of the path of movement of the panel to permit opening of the panel.

CLARENCE D. PLATT.
